UNITED STATES PATENT OFFICE

160,036

RUBBING MACHINE OR THE LIKE

Peter T. Triolo, Rockford, Ill., assignor to Sundstrand Machine Tool Co., Rockford, Ill., a corporation of Illinois

Application February 24, 1950, Serial No. 8,100

Term of patent 7 years

(Cl. D9—2)

To all whom it may concern:

Be it known that I, Peter T. Triolo, a citizen of the United States, residing at Rockford, county of Winnebago, State of Illinois, have invented a new, original, and ornamental Design for a Rubbing Machine or the like, of which the following is a specification, reference being had to the accompanying drawings, forming a part hereof.

In the drawings:

Fig. 1 is a side elevational view of a rubbing machine or the like, embodying my new design.

Fig. 2 is an elevational view looking at the left-hand end of Fig. 1.

Fig. 3 is a top plan view.

Fig. 4 is an elevational view looking at the right-hand end of Fig. 1.

The dominant features of the design are shown in full lines.

I claim:

The ornamental design for a rubbing machine or the like, as shown and described.

PETER T. TRIOLO.
